United States Patent Office

Des. 228,631
Patented Oct. 16, 1973

228,631

CART

Harry Rogove and Roslyn Rogove, Bayside, Queens,
N.Y., assignors to Remember When Sweet Shoppe, Inc.,
Valley Stream, N.Y.

Filed Aug. 29, 1972, Ser. No. 284,650

Term of patent 14 years

Int. Cl. D12—02

U.S. Cl. D12—22

FIG. 2

FIG. 1

FIG. 4

FIG. 3

FIG. 6

FIG. 5

FIG. 1 is a perspective view of a cart showing our new design;

FIG. 2 is a front elevational view;

FIG. 3 is a right side elevational view, the left side being substantially a mirror image thereof;

FIG. 4 is a top plan view;

FIG. 5 is a rear elevational view; and

FIG. 6 is a top plan view of the cart shown in FIG. 1, with the canopy thereof removed.

We claim:

The ornamental design for a cart, as shown and described.
